COLLECTION BOX

Chris T. Shagla, Ellicott, N.Y.
(Apple Inn, R.D. 1, Jamestown, N.Y.)

Filed Mar. 13, 1961, Ser. No. 64,231

Term of patent 14 years

(Cl. D34—5)

FIG. 1 is a front elevational view of a collection box, showing my new design;

FIG. 2 is a side elevational view thereof; and

FIG. 3 is a top plan view thereof.

The rear and the side not shown are identical with the front and side shown in FIGS. 1 and 2, respectively.

I claim:

The ornamental design for a collection box, substantially as shown and described.
